UNITED STATES PATENT OFFICE.

WALTER LARKIN, OF NORRISTOWN, PENNSYLVANIA, ASSIGNOR TO FIDELITY MACHINE AND MANUFACTURING CO., OF PHILADELPHIA, PENNSYLVANIA, A CORPORATION OF PENNSYLVANIA.

DOGLESS ATTACHMENT FOR RIBBERS.

Application filed April 9, 1920. Serial No. 372,494.

To all whom it may concern:

Be it known that I, WALTER LARKIN, a citizen of the United States, residing in Norristown, Pennsylvania, have invented Dogless Attachments for Ribbers, of which the following is a specification.

This invention relates to that class of mechanism designed to prevent the relative rotation of the dial and cylinder of a circular knitting machine while supporting the dial in its required position and permitting the delivery of yarn to the needles.

One object of the invention is to provide a novel device of the above class which shall not require movable dogs or pawls with a ratchet wheel, and a cam for actuating said pawls; the invention contemplating novel means for preventing rotation of the dial post while permitting rotation of the yarn 20 coaxially therewith.

I further desire to provide an attachment for a knitting machine of the class described in which the dial and its post shall be supported by the yoke which cooperates with said post, and a spider to prevent rotation of the post and its dial, while permitting rotation of the yarn about the post; the construction being such as to permit the cylinder and dial being rotated on their vertical 30 axis to enable an operator to inspect or operate upon the rear parts of these elements or their associated structures.

I also desire to provide a knitting machine with a dogless attachment including a novel combination of parts whereby the dial post with the dial and its associated cams may be quickly and conveniently removed from or inserted in the machine;—the invention including also conveniently 40 operative means whereby the post may be adjusted vertically to vary the relative position of the dial and cylinder.

Another object of my invention is to provide a dogless attachment for knitting machines, which by avoiding the use of pawl and ratchet mechanism or equivalent devices, shall be more reliable in operation, inexpensive and simple in construction and of such nature as to require but a minimum of 50 attention under conditions of use.

These objects and other advantageous ends I attain as hereinafter set forth, reference being had to the accompanying drawings, in which,

Fig. 1 is a vertical section, illustrating a knitting machine constructed in accordance with my invention;

Fig. 2 is a plan of the upper part of the machine shown in Fig. 1;

Fig. 3 is a plan partly broken away, illustrating a slightly modified form of the invention; and

Fig. 4 is an elevation partly in vertical section further illustrating the structure shown in Fig. 3.

In Figs. 1 and 2 of the above drawings, 1 represents the upper part of the frame of a knitting machine on which is mounted an adapter ring 2 carrying the stationary needle cylinder 3. Between said ring and the surrounding part of the frame is mounted a bevelled rack or gear 4 which is fixed to the rotating cam ring 5, and is driven by any suitable mechanism. These parts are held in position by a retaining ring 6 carrying 75 in the present instance three posts 7 serving to support a spider 8. These posts are mounted on a portion of the ring somewhat less than 180 deg. in angular extent and the spider itself consists of a segmental structure 9 of less than 180 deg. angular length, with which the spider arms are integral. This portion 9 of the spider is internally 80 concentric with the needle cylinder 3.

The customary cams for the control of the 85 needles on the cylinder 3 are carried by the rotating cam ring 5 and by the cam ring cap 10 which is mounted thereon, and said cam ring also serves as a support for a pair of oppositely disposed posts 11 carrying the 90 yoke 12 whose central portion or hub supports and is fixed by pins or screws 15 to the flange 13 of a yoke bushing 14. Passing centrally through the bushing 14, which extends both above and below its flange 13, is 95 the dial post 16 having fixed to its lower end the dial 17 and also having rotatably mounted on it a dial cap 18. The latter is provided with a laterally projecting arm 19 engaged by a pin or post 20 extending downwardly from the yoke 12 so that it is rotated therewith.

The yoke bushing and therefore the post 16 extending therethrough, is laterally held and steadied by a centering ring 21 formed 105 with a flange resting upon and removably fixed by screws 30 to the flat top surface of the spider segment 9 from which it extends

downwardly to provide a bearing for the edge of said flange. As above noted, the spider segment 9 is circularly curved concentric with the needle cylinder, and while the 5 centering ring 21 provides a circular bearing for the flange 13 of the bushing 14 which is also concentric with the needle cylinder and dial post; the upper part of said ring is formed with a circular opening which is eccentric both to the spider segment and to the 10 needle cylinder. In this opening is rotatably mounted an externally flanged yarn carrier ring 22 concentrically bored to rotatably receive an eccentric 23 on the dial post 16 which passes eccentrically through it. Said eccentric is recessed to receive or fit over the 15 upper end of the bushing 14 and the weight of the dial post with the dial etc. is transferred to said eccentric through an adjusting 20 cap 25 pinned to said post, there being an adjusting screw 26 extending vertically through said cap so as to bear on the eccentric. Said cap is preferably flanged so as to fit down over the upwardly projecting portion 25 of the eccentric 23 in order to keep the dial post from turning. The yarn carrier ring 22 has a downwardly flaring passage 27 for the yarn while a similar upwardly flaring passage 27^a is formed through the flange 30 13 of the bushing 14, and in order that the yarn carrier ring may be turned with the yoke 12 and the bushing, I connect it to the flange 13 of the latter by a link 28 one end of which receives the pin 20 while the other is 35 connected by a pin 29 to said ring.

With the above described arrangement of parts, power is applied to the gear 4 to turn the cam ring 5 in the well known manner, and the posts 11 with the yoke 12 and bushing 40 14 being mounted on said cam ring, are necessarily turned therewith. The bushing 14 through the link 28, consequently causes the yarn carrier ring 22 to rotate in the centering ring 21, so that the yarn is free to pass through the channels 27 and 27^a to the 45 needles of the machine. Since the eccentric 23 is rigidly fixed to the dial post 16 through the cap 25 and the pin 25^a, and since said post is axially centered by the bushing 14 and yoke 12, it is held from rotation axially by the eccentric 23, which necessarily remains stationary within the rotating yarn carrier ring 22. The dial post and the dial are hung from the cap 25 which is supported 50 55 from the yoke as above described, and the dial may be adjusted vertically relatively to the cylinder by suitable manipulation of the screw 26.

If for any reason it should be desired to 60 temporarily increase the space between the dial and cylinder needles, said post with the dial may be raised by lifting them with the cap 25 and eccentric 23 and if desired, inserting a piece of material under said eccentric. When desired, removal of this piece

will permit the dial post with the dial to be lowered to its original position relatively to the needle cylinder.

When the dial post with its associated parts is to be removed this may be accomplished with the utmost convenience by removing the screws 30 whereby the centering ring 21 is held to the spider 8 and thereafter taking off the nuts 31 which hold the yoke 12 to the posts 11. Thereupon the yoke with its associated parts, etc. may be raised to free its arms from said posts, and by inclining the dial post away from the spider 9, it with the various disks, bushings, etc. may be removed from the machine. By extending the centering ring downwardly to provide a bearing for the outwardly extending flange 13 of the bushing 14, the post 16 is materially steadied, and is held by this means from possible gyratory movement under operating conditions.

If it be desired to simplify the construction of the machine, I may form the centering ring as shown at 21^a in Figs. 3 and 4, and omit the downwardly extending bearing for the flange of the bushing 14 which would thus have no side bearing or support. As in the other form of my invention however, the dial adjusting cap 25 rests upon the eccentric 23, which through the bushing 14 is carried upon the yoke 12.

From the above description it will be noted that my machine altogether avoids the necessity for such devices as cams and pawl-and-ratchet mechanism for holding the dial post and dial from rotation while providing them with the necessary support, and permitting passage of the thread to be knitted. Obviously the construction is simple, substantial and of such a nature that even though the parts become worn, there is no danger of their failure to operate such as would occur when the pawls ordinarily employed do not function properly.

In order to permit the operator of the machine to make any inspection or repair of the rear side of the needle cylinder or dial, etc. while standing in front of the machine, I provide the adapter ring 2 with a flange 51 rotatably fitting inside of the circular opening of the main frame 1, connecting these parts by screws such as indicated at 52. With this arrangement it is possible, by removing said screws and the screws connecting the dial centering ring with the spider, to turn the cylinder, dial post and their associated parts on the vertical axis of the cylinder through any angle, usually 180 deg. so that the rear parts of these elements are brought to the front of the machine, and may be readily adjusted, cleaned, or examined.

It is noted that while in Fig. 1 I have shown the yarn guides 27 and 27^a as in the vertical plane including the yoke 12, and its

posts 11, this has been done to illustrate the relation of these guides to each other, since they are preferably displaced to a greater or less degree to one side or the other of the 5 vertical plane of said yoke and posts as indicated in Fig. 2.

I claim:

1. The combination in a rib knitting machine of a cylinder; a dial; a rotary yarn 10 guiding member; and means for holding the dial from turning relatively to the cylinder including a structure eccentric to the dial and concentric with the yarn guiding member.

2. The combination in a rib knitting machine of a cylinder; a dial; rotary cam 15 mechanism for the cylinder and dial; means for supporting the dial; a relatively fixed structure; and elements including a stationary eccentric cooperating with said structure for preventing rotation of the dial.

3. The combination in a rib knitting machine of a cylinder; a dial; a ring mounted eccentrically to the axial line of the dial and having a yarn guide; means for turning said 25 ring; with a structure connected to the dial and held from rotating by said ring.

4. The combination in a rib knitting machine of a non-rotating needle cylinder; a dial; cam rings; means for rotating said 30 rings; a locking device including an eccentric for preventing rotation of the dial; with a rotary yarn guiding member holding said eccentric from turning and journaled in a relatively stationary part of the machine.

5. The combination in a rib knitting machine of a frame; a cylinder; a dial; means including a relatively rotary structure for supporting the dial; rotary cam mechanism 35 for the cylinder and dial; a rotary member supported by the frame for guiding the yarn to the needles; with an eccentric maintained in a fixed position by said member and holding the dial from rotating.

6. The combination in a rib knitting machine of a cylinder; a dial; a dial post; rotary cam mechanism for the cylinder and dial; a rotary yarn guide; a stationary structure engaging the yarn guide; and a member continuously held immovable by the stationary structure acting through the yarn 45 guide for preventing rotation of the dial post and dial.

7. The combination in a rib knitting machine of a cylinder; a dial post; a relatively 50 stationary structure; a yarn guide mounted thereon and rotatable eccentrically to the post; an eccentric on the post held from rotating by said yarn guide; a rotary cam ring; and a structure mounted thereon for supporting the dial post and dial.

8. The combination in a rib knitting machine of a cylinder; a dial post; a relatively 55 stationary structure; a yarn guide mounted thereon and rotatable eccentrically to the post; an eccentric on the post held from ro-

tating by said yarn guide; a rotary cam ring; and a structure mounted thereon for supporting the dial post and dial; with means for vertically adjusting the dial post.

9. The combination in a rib knitting machine of a cylinder; a dial; a dial post; a rotary structure providing a vertical bearing for said dial post and also supporting the same in a predetermined vertical position; a relatively fixed structure extending 70 adjacent the dial post; a yarn guiding member having a bearing on said fixed structure and driven by said rotary structure; with a relatively fixed element engaging said rotary member and normally preventing rotation 75 of the dial post and dial.

10. The combination in a rib knitting machine of a frame; a cylinder; a dial; a cam mechanism for the cylinder and dial; a rotary yoke supporting the dial; a yarn guiding member rotatable with the yoke and having a bearing in a part of the frame; with an eccentric engaging the yarn guiding member and holding the dial post from turning.

11. The combination in a rib knitting machine of a frame; a cylinder; a dial; a dial post supporting the dial; cam mechanism for the cylinder and dial; a rotary yoke; a flanged bushing fixed to the yoke and rotatably engaging the dial post; a member connected to the frame and providing a bearing for the flange of said bushing; a rotary yarn guide driven from the yoke and having a bearing in said member eccentric to the dial 95 post; and an eccentric fixed to the dial post held from turning by said yarn guide.

12. The combination in a rib knitting machine of a frame; a cylinder; a dial; cam mechanism for the cylinder and dial; a 100 dial post; a rotary structure vertically and laterally supporting the dial post; and means for holding the post from turning consisting of an eccentric, a rotary member held from bodily movement by the frame 110 and engaging the eccentric, with a member fixed to the dial post separably engaging the eccentric to prevent rotation of the post relatively thereto.

13. The combination in a rib knitting machine of a frame; a cylinder; a dial; cam mechanism for the cylinder and dial; a dial post; a rotary structure vertically and laterally supporting the dial post; means for holding the post from turning consisting of 115 an eccentric, a rotary member engaging the eccentric and held from bodily movement by the frame; and a member fixed to the dial post separably engaging the eccentric to prevent rotation of the post relatively thereto; with means for adjusting the post relatively 120 to the eccentric.

14. The combination in a rib knitting machine of a frame; a cylinder; a dial; cam mechanism for the cylinder and dial; a dial 125

post; a rotary structure vertically and laterally supporting the dial post; means for holding the post from turning consisting of an eccentric, a rotary member engaging the eccentric and held from bodily movement by the frame; a member fixed to the dial post separably engaging the eccentric to prevent rotation of the post relatively thereto; with means for adjusting the post relatively to 10 the eccentric, consisting of an element threaded into said member and engaging the eccentric.

15. The combination in a rib knitting machine of a frame; a cylinder; a dial; cam mechanism for the cylinder and dial; a dial post; a structure carried by the frame and including a segmental structure above the cylinder; a centering ring removably mounted on said structure and having a bearing 50 eccentric to the dial post; a yarn guiding ring rotatable in said bearing; means for driving said ring; with an eccentric in the ring connected to the dial post for holding the latter from turning.

20 16. The combination in a rib knitting machine of a frame; a cylinder; a dial; a dial post; cam mechanism for the cylinder and dial; a rotary structure vertically and laterally supporting the dial post and dial and including a removable yoke supporting 55 said post; a centering ring; means for separably carrying said centering ring from the frame to permit of its removal horizontally therefrom; a yarn guide having a bearing in said centering ring; with an eccentric connected to the dial post and held from rotation therewith by the yarn guide.

25 17. The combination in a rib knitting machine of a frame; a cylinder; a dial; a dial post; rotary cam mechanism for the cylinder and dial; posts rotatable with said cam

mechanism; a yoke removably mounted on the posts; a bushing for the dial post supported on said yoke; an eccentric fixed to the dial post and having a bearing on said 45 bushing; a yarn guide rotatable relatively to the eccentric; a segmental structure mounted on the frame adjacent said yarn guide; a centering ring removably carried by said structure and providing a bearing 50 for the yarn guide; with means for rotating said ring.

18. The combination in a rib knitting machine of a cylinder; a dial; a rotary yarn guiding member; means for holding the dial 55 from turning relatively to the cylinder including a structure eccentric to the dial and concentric with the yarn guiding member; with a guide for said eccentric structure permitting vertical movement thereof when 60 it is desired to raise the same to increase the space between the dial and cylinder.

19. The combination in a rib knitting machine of a cylinder; a dial; a dial post; a rotary yarn guide; a relatively fixed supporting structure; an eccentric fixed to the post and cooperating with the yarn guide to hold said post from turning, said eccentric and post being movable vertically relatively to the fixed supporting structure.

20. The combination in a rib knitting machine of a needle cylinder; a dial; a rotary yarn guide; a post supporting the dial eccentrically to the path of movement of said guide; an eccentric fixed to the dial post for 75 holding the same from turning; a cap fixed to the dial post above the eccentric; with a structure vertically supporting the eccentric with the dial post and dial, the latter parts being free to be moved vertically relative to the needle cylinder.

WALTER LARKIN.
